UNITED STATES PATENT OFFICE

DUANE L. POTTER, OF DALTON, PENNSYLVANIA

POLICE STICK

Application filed April 24, 1929. Serial No. 357,803.

This invention relates to batons or police-men's sticks, and more particularly to the type which provide means for preventing the stick from being wrested from the police-
5 man's grip.

The principal object is to provide a stick to be used by peace officers or policemen, whereby the stick may be used in subduing an unruly prisoner, and at the same time, should 10 the prisoner attempt to wrest the stick from the officer's grasp, the officer may, by exerting a slight pressure against the rear end of the stick, cause blades to move outwardly from the stick so as to present a cutting edge 15 to the prisoner's grasping hand.

Another object is to provide a stick which, under normal conditions, will present the appearance of an ordinary baton or police stick, and yet contains means for breaking the 20 grasp of an unruly prisoner should he attempt to take the stick from the officer. The means are controlled by the pressure of the hand.

The idea of having means in the striking 25 part of the stick which will project therefrom so as to break the prisoner's grasp should he attempt to wrest the stick from the officer is old; but heretofore, the means for causing the projections to extend from the 30 stick has not depended upon the pressure exerted by the hand of the officer in gripping the stick.

In the drawings:

Figure 1 is a perspective of the stick in 35 operation;

Figure 2 is a section taken along the line 2-2 of Figure 3;

Figure 3 is a side elevation;

Figure 4 is an end elevation of Figure 3;

Figure 5 is a section taken on the line 5-5 40 of Figure 3; and

Figure 6 is a perspective of the cutting blade removed from the stick.

Referring to the drawings, in which similar numerals designate like parts.

Numeral 1 refers to a police stick having cutting blades 2 in grooves 3, the rear portion of the cutting edge 2 having gripping members 4 curved outwardly from the rear 50

portion of the stick 1. Intermediate the cutting edges 2 and gripping members 4 are pivotal members 5 in the form of shoulders through which pivot pins 6 pass. The rear portions of the grooves 3 are cut away so as 55 to leave sufficient space between the gripping members 4 and the bottom of the grooves to insert flat springs 7, which are held in place against the gripping members 4 by sleeves 8, into which the springs 7 are inserted. 60

As actually used, the blades 2 will be entirely below the striking surface of the stick 1 at all times, except in the event of the prisoner attempting to wrest the stick from the hands of the officer. 65

It will be noted that the cutting blades 2 are pivoted at 5, and that the handle portions 4 of the cutting blades 2 extend from the rear of the stick 1 at an upward and downward angle, respectively. As the stick is normally 70 grasped, it will be impossible for the cutting blades 2 to be raised above the striking surface of the stick 1. It is only upon the prisoner grasping the end of the stick and pulling on the same and forcing the officer's 75 hand to the rear so as to encounter the gripping members 4 that the cutting blades 2 will be forced from the stick. These will bear against the grasping hand of the prisoner, and force him to relinquish his grasp thereon. 80 As soon as the officer's hand is removed from the gripping members 4, and the stick normally grasped, the cutting blades 2, due to the flat springs 7, will return to their normal position below the striking surface of the 85 stick 1.

It is obvious from this, that only through the intention of the officer will the blades 2 be extended, and then, there must be a pulling force on the front end of the stick and the 90 officer must allow his hand to slide to the rear sufficiently to contact with the gripping members 4.

It is also apparent that due to the springs 7, 95 the cutting blades 2 will normally be encased in the grooves 3 below the surface of the stick 1.

It is understood that alterations and substitutions may be made in the above disclosure 100

within the scope of the claims without affecting the merits of this invention.

What I claim is:

1. A police stick comprising a cutting member normally below the surface of the stick, a gripping member integral with said cutting member pivotally connected to said stick for projecting said cutting member, means for returning said cutting member to its normal position.
2. In a police stick, the combination of a shaft; a lever pivoted intermediate the ends of the shaft, comprising a cutting member and a hand grip; and means for holding the cutting member normally within the surface of the shaft.
3. In a police stick, the combination of a shaft having a longitudinal groove and a lever pivoted in the shaft, one end of the lever having a cutting edge adapted to be projected from the groove and the other end having a hand grip for projecting the cutting edge.
4. In a police stick, the combination of a shaft having a longitudinal groove; a lever pivoted in the groove, having a cutting edge and a hand grip; and a spring normally holding the cutting edge within the surface of the shaft.
5. In a police stick, the combination of a shaft having a longitudinal groove; a lever pivoted in the groove, one end of which comprises a cutting member and the other end an outwardly extending hand grip; and a spring adapted to hold the cutting member within the surface of the shaft.
6. In a police stick, the combination of a shaft having longitudinal grooves; a lever pivoted in each groove, each lever comprising a cutting member and a hand grip; and springs adapted to hold the cutting members within the surface of the shaft.

In testimony whereof I affix my signature.
DUANE L. POTTER.
